US00D805146S

(12) **United States Design Patent** (10) Patent No.: **US D805,146 S**
 Clarke et al. (45) Date of Patent: **** Dec. 12, 2017**

(54) GOLF CLUB HEAD	D344,778 S	3/1994	Solheim
(71) Applicant: Karsten Manufacturing Corporation , Phoenix, AZ (US)	D346,840 S	* 5/1994	Fenton D21/751
	D357,293 S	4/1995	Solheim
	D357,294 S	4/1995	Solheim
	D368,127 S	3/1996	Solheim
	D376,632 S	* 12/1996	Simmons D21/750
	D379,393 S	5/1997	Kubica
(72) Inventors: Jacob T. Clarke , Phoenix, AZ (US); Ryan M. Stokke , Anthem, AZ (US); Xiaojian Chen , Phoenix, AZ (US)	5,658,209 A	8/1997	Blakemore
	D383,819 S	9/1997	Takahashi
	5,665,013 A	9/1997	Kobayashi
	5,676,605 A	10/1997	Kobayashi
(73) Assignee: Karsten Manufacturing Corporation , Phoenix, AZ (US)	D386,550 S	11/1997	Wright
	D386,551 S	11/1997	Solheim
	D387,405 S	12/1997	Solheim

(**) Term: **15 Years**

(Continued)

(21) Appl. No.: **29/559,195**

FIG. 1 is a top perspective view of a golf club head;
FIG. 2 is a bottom perspective view of the golf club head of
FIG. 1;FIG. 3 is a front view of the golf club head of FIG. 1;
FIG. 4 is a rear view of the golf club head of FIG. 1;
FIG. 5 is a top view of the golf club head of FIG. 1;
FIG. 6 is a bottom view of the golf club head of FIG. 1;
FIG. 7 is a left view of the golf club head of FIG. 1; and,
FIG. 8 is a right view of the golf club head of FIG. 1.
The broken lines shown in one or more of the figures are for
illustrative purposes only and form no part of the claimed
design.**1 Claim, 7 Drawing Sheets**US D805,146 S
